UNITED STATES PATENT OFFICE.

OTTO ASMUSSEN, OF BROOKLYN, NEW YORK.

AUTOMATIC SELECTING MULTIPARTY-TELEPHONE SYSTEM.

1,145,659.

Specification of Letters Patent.

Patented July 6, 1915.

Application filed March 21, 1913, Serial No. 755,852. Renewed May 25, 1915. Serial No. 30,462.

To all whom it may concern:

Be it known that I, Otto AsmusSEN, a subject of the King of Denmark, residing at Brooklyn, Kings county, and State of New York, have invented and discovered certain new and useful Improvements in Automatic Selecting Multiparty-Telephone Systems, of which the following is a specification.

The object of my telephone system is to provide a very economical plant, substituting for manual help reliable automatic operation, which at the same time responds to all the advantages that any telephone system offers the public, and with that aim in view this system has been contrived for the establishment of a mutual automatic interconnecting or exchange system between the subscribers in towns, cities and rural districts on a single metallic circuit system with additional earth connection, with the advantage that none of the intermediary stations or subscribers can either hear the calling, the ensuing conversation, or be able to interrupt connected parties, or take the line.

Small cities and rural districts can be connected and served on an interurban trunk line system. Such small cities and rural districts are provided with circular and terminal lines and the subscribers make their own local connections mutually by means of the automatic selecting apparatus, while a central office performs the interurban or long distance exchange connections, connecting automatically, and at a far distant point, the subscribers individually on one system with parties on another, carrying most advantageously an aggregated number of systems on one metallic trunk circuit.

In large cities a central office is established for which only very limited help is required, or if an automatic switching or exchange system be adopted, my system will in connection with such an automatic exchange system greatly reduce the expense of the costly switching apparatus in common use.

Long terminal and trunk or main lines are constructed so as to establish two telephone speaking circuits through above metallic circuit and earth connection, with the purpose of maintaining a quick service system. One circuit is used for ordering connections with subscribers, and this circuit will stand open for such short communications to the central office at all times. The ringing on

this circuit will not be heard by anybody, except by the central office. Connection between two parties is established at the first moment the lines are free, and the waiting party, who has ordered the connection, and the selected party, are both called up at the same time by the central office, and when the communicating parties unhook their receivers they are in communication together on the circuit reserved for conversation purposes, and nobody can, as per above, overhear the conversation, not even the switchboard operator.

As subscribers on circular systems and on some terminal lines in towns and small cities connect themselves mutually they do not request the central office for connections, except when connections over trunk lines, or an interurban exchange are required, and in that case the operator at the central office enters with his current the nearest system, sets the calling subscriber's apparatus in position for communication, leaves that system, and connects with the other city's system, where he sets the selected subscriber's apparatus in the same position, whereupon he rings both parties up at the same time, leaving all the other intermediary stations locked out of connection. Thus ramifying this telephone system, subdividing the work between the subscribers themselves and the few needed operators in the central office, receiving the subscriber's order for connection on a separate circuit, interconnecting trunk lines with city systems, establishing interurban connections between all the subscribers in many scattered towns and cities from a distant central office, has great advantages, and so much more so, as the automatic apparatus combination on circular systems and terminal lines, works to both sides, establishing connections backward just as well as ahead, so that many pairs of parties can speak together on the same line at the same time. The same system is an excellent vehicle for long distance telephone use, as it closes out every one not wanted on the line, excluding every possibility for anybody to disturb or intervene, and even the operator at the central office can be cut out.

A signal (not shown) on the apparatus at the subscriber's station will indicate when the line is free or occupied.

Three different line systems will be used in connection with this telephone plan, trunk lines, circular lines and terminal lines.

Trunk lines are established for interurban connections, and will connect a number of city systems automatically on one circuit. Circular lines are installed in small cities in 5 an endless continuation, or the ends are brought together in an interconnecting installation, so that they can be bridged over and form an endless circular circuit, and the ends can in this case be cut off at convenience. Terminal lines are established in 10 cities radiating to all sides from a central office and connecting a large number of subscribers through each circuit with that office. Circular and terminal systems are provided 15 with the automatic, subscriber, selecting apparatus, when no central office exists in the system. Subscribers on terminal lines in larger cities either connect themselves with one another, or they ask for connection from 20 the central office.

This invention therefore consists in the structure of parts and in their combination and association in electric circuits and systems to the attainment of the above object, 25 substantially as hereinafter set forth and claimed.

In the accompanying drawings, which form a part of this specification, the various apparatus have, in the main, been 30 shown coupled up in the system and yet have been given captions as though separately illustrated. This it is believed will simplify the disclosure of the invention, in much as the illustration of conjointly operating apparatus of one station is necessarily spread over the first three sheets of 35 the drawings. In this mode of illustration, circuits and sources of current are mainly represented diagrammatically or graphically. 40

Figure 1 depicts an automatic selecting apparatus; Fig. 2 a line changing apparatus; Fig. 3 a resetting apparatus; Figs. 4, 45 5, and 6 auxiliary switching apparatus; Figs. 6^a and 7^a modifications in auxiliary switching apparatus and in bridging relays; Fig. 7 a group of bridging relays; Figs. 8 and 9 a specially constructed set of interchanging apparatus; Fig. 10 a set of modified bridging relays; Fig. 11 a circular line system; Figs. 12, 13, 14, 15, 16, 17, and 17^a details of the automatic selecting apparatus; Fig. 18 a telephone switch connection at a 50 station; Fig. 19 a modification in the application of power to the auxiliary switching apparatus; and Figs. 20 and 21 detail views illustrating features of construction and arrangement on an enlarged scale.

In order that the coöperation of these several instruments may be better understood in the operation of this system, a detailed 60 description thereof will first be given.

The apparatus used for the local connecting and interurban exchange operations are 65 the following: The specially constructed

automatic, selecting apparatus is contrived for central station purposes. It is used in circular systems, in all the subscribers' places, and sometimes on terminal lines. It consists of an electrical driving motor, 70 Fig. 1, M, two connecting wheels, 20 and 21, and a numerated selecting disk, 22, this last being provided with numbered holes for insertion of a connecting plug, 113, which serves the purpose of setting the selected subscribers' apparatus for communication. All three wheels are fixed on an axis, 75 and are carried around together by the motor, which is fed by a local current from battery 23, forming its circuit through the retaining arrangement, 134, collecting brush 25, over stopping pin 128, wire 28, and back over wire 29. Through the special contact or connecting system used in this selecting apparatus it is possible to reverse 80 the current pulsations in a circuit alternatively and automatically.

The normal position of the collecting or connecting brushes 120 and 125, Fig. 1, is always resting on insulated plates, and the 85 spring contacts 118 and 123 are always arranged so that the first station, which is consequently the operating party's, is set for conversation without it being necessary to put in another plug for the setting of that instrument, so the plug for setting the selected party's apparatus for conversation is generally the only one to be inserted in the numbered hole in the selecting disk, 90 corresponding to the selected party's number. 95

The line changing apparatus, Fig. 2, is a specially constructed electro-magnet with an arch-shaped attachment, 30. It is designed for changing the lines from the selecting apparatus so that they shall co-operate either with the line ahead of, or on the line back of, the operating station. This instrument is not reset until all the other 100 apparatus on the line have been reset after a telephone conversation has taken place, except in stations where somebody has tried to take the line while it was busy. The resetting apparatus, Fig. 3, consists of a smaller motor M', a resetting wheel 31, and a plug supporting rack, 32, which serves as 105 a connecting and disconnecting arrangement. 110

The auxiliary apparatus of Figs. 4, 5, and 6, are electro-magnetic switches. The two coils of each instrument are both double wound for the purpose of differently and momentarily energizing the polarized armatures 33, 34, and 35, which are represented in their resting or normal position. Six 115 small polarized armatures 36, 37, 38, 39, 40, and 41, accompanying the magnets of these switches. The armature levers of these relays are momentarily attracted at 120 the moment a current passes those coils, 125 130

against contact posts which keep them from adhering magnetically to the armatures, or they release according to the energization or deenergization of said magnets. These

5 instruments are installed in all the subscribers' places. Arch switching attachments are built on the polarized armatures 33, 34, and 35 and they rock over with the armatures from the resting position R, to 10 the operating position O, and vice versa. When rocking over to the one or the other side, the connecting or conducting sleeves on the arch, separated by insulation, are thrown up or down between, or away from, the 15 roller contacts, signified by the small eyes on both sides of the arches, thus forming connection with them, or cutting the connection between same, every time the armature shifts. The armature 40 interrupts 20 line 1 every time it is attached, viz.: every time a current passes through the magnet coils, thereby preventing the current pulsation from going out on the line to disturb the position of the next station's instru- 25 ment, if the lever 49 of the bridging relay, Fig. 7, should fall back on its resting screw 60, before the contact wheels 20 and 21, Fig. 1, have finished their contact pulsation. These levers keep the line interrupted as 30 long as the current pulsation lasts. The armature 36 interrupts the line in the same way, but on the section back of the operating station.

The set of bridging relays, Fig. 7, consists 35 of two bridging relay coils, 44 and 45, four bridging levers, 46, 47, 48 and 49, two local current relays, 50 and 51, with relay levers 52 and 53. When the armatures 33 and 35, Figs. 4 and 6, are in resting position a local 40 circuit is maintained through the coils 44 and 45, Fig. 7, from gravity battery 54, Fig. 7, emanating from the carbon pole, flowing over wire 56, union 66, Fig. 4, armature 33, contact screw 65, wire 56', union 68, Fig. 6, 45 armature 35, contact screw 189, wire 56'', through bridging-relay coil 44, Fig. 7, over wire 56''', through bridging relay coil 45 and back over wire 56''', to the zinc pole of said battery. Every time anyone of the 50 auxiliary apparatus, Fig. 4 or 6, is rocked over to position O, this circuit is interrupted and all the four levers, 46, 47, 48, and 49, Fig. 7, fall back on their resting screws 57, 58, 59, and 60.

55 At certain operations it is necessary to have the levers 46 and 49, Fig. 7, remaining upright, or in vertical position, this is attained through the local current passing through one of the coils 50 or 51, Fig. 7, at 60 the rocking over into position O of the armature of the auxiliary apparatus, Fig. 5. This armature is only rocked over at the setting of a station for communication, (be it on the line ahead, which will be called the 65 northern section from the operating station,

or on the line back, which will be called the southern section from the operating station) and it is only then rocked over simultaneously with one of the armatures 33, Fig. 4 or 35, Fig. 6. At the moment these two rockings or shiftings of the armatures have taken place a local circuit is closed over same, the current flowing from the carbon pole of gravity battery 55, over wire 61, roller contacts 72, Fig. 5, connecting sleeve 73, roller contact 74, (the armature 34 is supposed to have rocked over to position O, so connecting sleeve 73 has advanced up between roller contacts 72 and 74 and forms connection with them) over wire 61', roller contacts and 75 conducting sleeve 75, 76, and 77, Fig. 6, (supposing it is that auxiliary apparatus that has rocked over, conducting sleeve 75 forms therefore contact between 76 and 77) over wire 61'', through coil of local current 80 relay 51, Fig. 7, and back over wire 61''' to the zinc pole of said battery. This sustains lever 49 in upright position until the apparatus are reset, whereafter it is upheld in the afore described way through local circuit current from battery 54. Had it been 85 the armature 33, Fig. 4, that had rocked over to position O, this current emanating from battery 55 would partly have taken the same way over wire 61, roller contacts and conducting sleeve 72, 73, and 74, Fig. 5, wire 61', but from union 78 it would flow over wire 79 to roller contacts and connecting sleeve 81, 80 and 82, Fig. 4, (conducting sleeve 81 is supposed to be thrown up between contacts 80 and 82) over wire 79', through coil of local current relay 50, over wire 79'' and back to the zinc pole of battery 55. This shows that if the armature 35, Fig. 6, is thrown over, the lever 49, Fig. 7, is 90 sustained in upright position, and the other levers 46, 47 and 48 will fall back, but if the other armature 33, Fig. 4, is thrown over, the lever 46 is upheld and the other levers 47, 48 and 49 fall back, whereas, if armature 34, Fig. 5, is not thrown over, no levers are sustained in upright position, as the circuit through roller contacts 72 and 74, Fig. 5, is broken through an insulating sleeve 95 when in normal position, as shown in the 100 design. The rocking over of either one of these armatures, Fig. 4 or 6, makes all the four bridging relay levers 46, 47, 48, and 49, Fig. 7, fall back and thus lock the stations 105 out of connection everywhere this operation 110 is performed.

The specially constructed set of interchanging apparatus of Figs. 8 and 9 is another set of electro-magnetic switches, with arch switching attachments, 83 and 84, built 115 on the polarized armatures 85 and 86. Four small armatures 87, 88, 89, and 90, accompany the operating magnets and their object will be explained below. The set of bridging relays, Fig. 10, has two coils 91 and 92, 120

two levers 93 and 94, and a focal current relay 95, which sustains the lever 94 in upright position by means of battery 96, which is in circuit through it, when the armature 85, Fig. 8, has rocked over to position O, over wire 98, roller contacts and conducting sleeve 99, 100, and 101, (the armature is supposed to have rocked over and conducting sleeve 100 in position between contacts 99 and 101) wire 98', through coil of relay 95, over wire 98'' and back to the zinc pole of said battery 96. This circuit sustains the lever 94 in upright position until the resetting of the instruments is done. Battery 97 10 maintains current over two circuits when the auxiliary apparatus, or both armatures 85 and 86, are in resting positions. This current flows from the carbon pole of battery 97, Fig. 10, over wire 102, Fig. 8, union 104, armature 85, contact screw 103, wire 102', through coil 91, Fig. 10, over wire 102'' and back to the zinc pole of battery 97. The other circuit is over the same wire 102, union 105, where it parts from the first described 20 path, over wire 106, union 107, Fig. 9, armature 86, screw contact 108, wire 106', through coil 92, Fig. 10, over wire 106'' and back to the zinc pole of said battery. This keeps the levers 93 and 94, Fig. 10, attracted to 30 contact posts 109 and 110, when the armatures 85 and 86 are in resting position. The bridging relays 91 and 92, Fig. 10, have each their separate circuit.

The circular line system, typified in Fig. 11, represents a number of stations (three) with an extra line L. 3, for trunk line service. This extra line is not necessary in making interurban connections, but may be very convenient. It is only used in cities and 35 towns where a larger number of subscribers are connected, but not on the trunk lines L. 2 is always insulated at the extreme ends on trunk and terminal lines, and a breach can also be made in circular systems, but this makes no difference in that system, so when a subscriber on a circular, terminal or trunk line calls up the central office, ordering connection with some interurban subscriber, he depresses the key 112, Fig. 11 and Fig. 6, and 40 he rings the usual call bell, (not shown). This key connects his telephone with L. 2 and earth with the central office, (as per above, L. 2 is interrupted at the extreme end, and has no other path than to the central stations). The connection with L. 1 is 45 interrupted in the switching attachment of the auxiliary apparatus Figs. 4 and 6, which will be seen later on, so the operating party sends his message to the central office while 50 depressing that key all the time he speaks. After that the subscriber releases his key. Then the central office sets for communication both his apparatus and that of the party in the other city to whom he wants to 55 speak, and both are rung up at the same

time and the conversation is carried over L. 1 and earth. In cities where said extra wire or line is used, each subscriber has two extra auxiliary apparatus installed, like those represented in Figs. 4 and 5, or 5 and 6, for the extra interurban connecting purposes, but no extra selecting or resetting apparatus is required. The telephones and auxiliary apparatus are only graphically represented in Figs. 11. 75

The sectional cut or view, Fig. 12, is of the back side 20' of connecting wheel 20, showing a series of radial spring contacts. Compared with sectional cuts, Figs. 1 and 16, it will be seen that when the plug 113 is inserted in the contact wheels, the radial spring 114 is pushed out, this interrupts the L. 1 south, but it leaves the L. 1 connected to the north. This is arranged with the object of interrupting the connection of the circular line, always cut at the operating station, so as to give the emanating currents the right direction over the one or the other section. L. 1 south is connected with the underlying connecting plates 115, Figs. 12 and 16, and L. 1 north to the set of radial springs 114, at connecting screw 301, Fig. 1. When both sets of these radial springs are in normal position the connection between the two sections of line 1 is established, but as soon as one of the radial springs is pushed out, this connection is broken to the southern section. 90

The sectional view, Fig. 13, is of the front side 20" of contact wheel 20, showing the 100 spring contacts 117 and the series of contact plates 118, see Fig. 16. These contact plates are connected with a conduction rail 119, Figs. 13 and 16, and this constitutes a link in the connection from battery 121 to L. 1 north. The lower parts of contact springs 117 are all connected together with L. 1, Fig. 13. As the series of contact springs 117 are standing out from the connecting rail 119, the connection from battery 121 to L. 1 is interrupted when in normal position, whereas connection is established as soon as one of those spring contacts is pushed back against the rail 119 by the insertion of the plug 113. The contact plates 118 have insulating spaces between them, Fig. 13. When the said plates come successively in contact with connecting brush 120, current pulsations flow from battery 121 out on L. 1. There is one spring contact 117 and one connecting plate 118 for each subscriber, or station, on the line. This wheel's pulsating current throws over all the first auxiliary apparatus, Fig. 4 or Fig. 6, on the line, locking all intermediary stations out of connection, as all the plates representing the number of intermediary stations are all brought in contact successively with brush contact 120. 115

The sectional view, Fig. 14, is of the back 120

side, 21' of connecting wheel 21, and it shows a series of radial spring contacts, 123, each with its contact plate 124 on top. These plates are set with di-electric spaces 5 or with insulating plates between the connecting plates, and all are connected with earth, Figs. 1 and 14. When the plug is inserted it pushes out one of these spring contacts 123, as shown in Figs. 1 and 16, and 10 with the rotary movement of the wheels, the contact plate 124, Fig. 14, comes in touch with connecting brush 125, this connects the battery 122 with earth over connecting plate 124, Fig. 14, and connecting screw 126, Fig. 15. There is in wheel 21 a radial spring with 15 its contact plate for each station on the line. The sectional view, Fig. 15, is of the front side 21'' of contact wheel 21. This cut, together with the design of Fig. 1 and the cut 20 of Fig. 16, illustrates the connections and circuit for the local motor battery 23. The contact plates 127 are to be put as close together as the movement back and forward will allow. They form a series of contact 25 plates on the front part of the series of springs 123, each of them is connected with a circular wire 129, Fig. 15, and this is connected with the local battery 23. When these springs are in normal position their 30 contact plates 127 touch connecting brush 25, Fig. 15, and 16, wherewith the motor circuit is closed through the stopping pin 128, as soon as the motor revolves. When the wheels remain in their stationary position this local circuit is interrupted by the retaining pin 26, as will be described below. When plug 113 is inserted in the hole bearing 35 the number of the subscriber who is to be called, it pushes the corresponding contact 123 out, Figs. 1 and 16, leaving an empty space, 130, Fig. 16, in the wheel. Through the rotary movement of the wheels, plug 113 is moved around with them, and it comes across the stopping pin 128, Figs. 1 40 and 16, (which pin is always in fixed position, as are the contact brushes 120 and 125) and that stops the movement of the wheels. At the moment the wheels stop, the contact 45 brush 25 slips into the empty space 130, Fig. 16, and breaks therewith the local motor current. This is provided in order not to waste uselessly the current while conversation is going on. The pushed out spring of series 123, Fig. 1, sets the selected station for conversation at the moment the plug causes the stopping, and all the other 50 intermediary stations have then been locked out through current pulsations over contact 118, Figs. 1 and 13. This is now the position of the selecting apparatus when the operating party can call up. When the conversation is finished and the plug is taken out, the pushed out spring 123 falls back on contact brush 25, Figs. 1 and 16, 55 wherewith the local motor circuit is estab- lished again and the motor moves until it is stopped by the retaining pin 26, Figs. 1, 17 and 17^A. At the moment this plug is taken out, the spring contact 117, Figs. 1, 13 and 16, stands out from its connecting rail 119, Figs. 1 and 13, and connection from battery 121 with L. 1 is interrupted, and when the wheel moves farther around till it reaches its stationary place, it moves then without pulsating any current into the 75 main line. There are none of the radial contact springs 123, Figs. 1 and 16, pushed out to cause current pulsations from battery 122, so this movement does not perform any operation on the main lines at all. Retaining pin 26, Figs. 1 and 16, stops the wheels, 80 interrupting the local current, and keeping the motor in its stationary position.

The selecting disk 22, Figs. 17 and 17^A, is provided with a circular connecting or 85 conducting rail or strip, 133, which has a retaining clip 134, Figs. 1, 17, and 17^A, made to stop the wheels, and at the same time to interrupt the local motor current circuit. This conducting strip ends in a spring contact tongue, 132, Figs. 17 and 17^A, which closes the circuit when raised against the retaining clip 134, and interrupts it when pressed down by the retaining pin 26. This pin remains always in a fixed position, while 90 the retaining clip is carried around with the wheels and comes across said pin at the stationary point. This stationary place responds to the subscription number of the operating party. If subscriber number 10 100 has finished conversation, the wheels will stop at number 10, and if subscriber number 50 has operated connection with somebody, his wheels will stop at his number. Fig. 1 gives a general view of the local battery wires, passing over the retaining arrangement, 134, from there it passes to the 105 conducting plates 127, Fig. 15, over contact brush 25, stopping pin 128 to the motor and from there back to the zinc pole. This explains that there are two stops of the wheels in each rotation, the first when the plug 113 comes across stopping pin 128, and the next is at the stationary place, and interruptions in the local current are caused as shown at 110 130, Fig. 16, and 124, Figs. 17 and 17^A. To put the motor in rotary movement the retaining pin 26 is pulled out an instant, 115 wherewith the contact tongue 132, Figs. 17 and 17^A, is released and comes in contact with retaining clip 134. This closes the motor circuit and starts the wheels forward, and when the pin 26 is released again and it drops behind the retaining clip. The tongue 132 can be replaced by a hook-like 120 spring similar to spring 223, Fig. 3, this is lifted from its contact clamp 231 by the plug when the wheel is finishing its rotation, and the hook-shaped spring retains it, so 125 when the plug, or in this case the retaining 130

pin, is pulled out the spring drops down on its contact clamp and the pin can thus be dropped immediately after having been pulled out without causing it to drop on any 5 retaining arrangement before the wheels start moving.

The telephone, Fig. 18, is installed in connection with the auxiliary apparatus and the key 112, Fig. 6, is for use in calling up the 10 central offices on the trunk lines. Another key 137 may be installed for the purpose of excluding the central office from overhearing the conversations, and the subscriber nearest the central office depresses that key, 15 interrupting the line to that side.

The combination, represented in Fig. 19, is contrived with the object of augmenting the magnetic force of the auxiliary apparatus, if that should be required on long distance lines for the shifting of the armature and the arch switching arrangement. For this purpose the polarized armature, 138, is provided at its ends with two fixed short cores, 139, 140, which move up and down 25 with the rocking of the armature in two solenoids 141 and 142, when a circuit is closed through one of them. These armatures are drawn down into the solenoids, at the same time as the main line current attracts 30 the armature 138. The very same instant that the main line current passes the magnet coils 143 and 143', the levers 144 and 145, are attracted by the cores of those coils against stops 146 and 147. This closes, a 35 local circuit from battery 148, through that set of roller contacts and conducting sleeve which is ready in the switching arrangement for it. If the magnet is in resting position R, the roller contacts and conducting sleeve 40 149, 150 and 151 are the ones forming the path for it. The current flows from carbon pole of battery 148, over wire 152, relay lever 153, wire 155, relay lever 145 (which is attracted) stop 147, wire 155', through solenoid 142, roller contacts and conducting sleeve 149, 150 and 151, back to the zinc pole over wire 156. This helps the main current (whose path is not indicated in the design) to rock the magnet over into position 45 O. Supposing the switching attachment is in position O, and it is the resetting current that comes in through the coils, then the insulating sleeve 158 has been thrown down between the contacts 149 and 150, so this 50 path is interrupted, but another over roller contacts and conducting sleeve 159, 160 and 161 is formed. The current flows consequently, at the moment the levers 144 and 145 have been attracted, from the carbon 55 pole of battery 148 over wire 162, relay lever 154, wire 163, relay lever 144 (which is attracted) stop 146, wire 164, through solenoid 141, over roller contacts and conducting sleeve 159, 160 and 161 (conducting sleeve 60 65 has by the magnet's rocking over been

thrown up between contacts 159 and 160) over wire 165 and back to the zinc pole of said battery. This will greatly strengthen the magnetic forces. Otherwise a local current can more simply be let through the 70 magnet coils 143 and 143' in the same direction as the main line currents.

The practical use of the system is the following: Suppose a station, 10 for instance, in a system where the subscribers make their 75 own connections, wants to communicate with a station 50, the operating subscriber takes the plug 113, Fig. 1, from the supporting rack 32, Fig. 3, and puts it into hole number 50 of the selecting disk 22, Figs. 1 and 16. 80 This establishes the above described connections. The spring contact corresponding to number 50 in the series 123 is pushed out by the plug, which is provided with shoulders for the object of pushing back simultaneously the spring contact 117 and spring 114, 85 Fig. 1. Spring contact 117 comes therewith in contact with conducting rail 119. When a pull is made on the retaining pin 26, the local motor circuit is closed and the selecting 90 apparatus revolves.

As the first station to be set for communication is the operating party's in all cases, the respective contact 118 and spring 123 are permanently set so that they cause the 95 setting of that first station without needing the insertion of a plug (contact 118 of station 10 is to that end connected directly with the introduction wire to line 1, that is to say to wire 167, and spring 123 in this station does not leave any empty space 130, Fig. 16,—this is filled out—to break the local current), and as per above, contact brushes 120 and 125 are resting in normal 100 position on insulated plates, which admits this permanent arrangement. The first current pulsations flow from both batteries 121 and 122, Fig. 1, at the same time for the setting purposes of station 10. That from battery 121 flows over contact brush 120, conducting rail 119, spring contact 117, union 166, wire 167, roller contacts and conducting sleeve 168, 169 and 170 of line changing apparatus Fig. 2, over wire 293, Fig. 2, union 110 302, wire 171, (it cannot go backward over wire 171 as the path is interrupted at roller contacts 278 and 279) farther ahead over wire 171, Fig. 7, lever 49 of bridging relay 45 connecting post 172, wire 173, roller contacts and conducting sleeve 174, 175 and 176, Fig. 6, through first winding of magnet coils 177 and 178, wire 179, union 180 and back over line 2 to the zinc pole of battery 121. At the moment the current passed coils 177 and 178, the armature 35, Fig. 6, 120 rocked over to position O, and the arch switching attachment changed the connections, and in the above described way the local current from battery 54, Fig. 7, having 125 its circuit over wire 56, union 66, Fig. 4, 130

armature 33, contact screw 65, wire 56', union 68, Fig. 6, contact screw 189, wire 56'', coils 44 and 45 of the bridging relay, Fig. 7, and back to the zinc pole of said battery, 5 was interrupted at contact screw 189, Fig. 6, and all the levers 46, 47, and 48, Fig. 7, fell back. The lever 49 gets no time to fall back as will be seen in the following. At the same time that battery 121 sends current 10 over L. 1, another current pulsation flows down through earth from battery 122, Fig. 1, over contact series 123, union 126, through earth, up over wire 180', Fig. 6, (the only path open for it) over relay lever 41, (which 15 is at that moment attracted against stop 181 by main current from battery 121 flowing simultaneously through coils 177 and 178) over wire 182, roller contacts and connecting sleeve 183, 184 and 185, Fig. 5, through 20 first winding of magnet coils 186 and 187, over wire 188, union 189 and back to zinc pole of battery 122 over L. 2. At the moment this current passed the coils 186 and 187 the magnet 34 with its switching attachment was thrown over to position O, a 25 local circuit from battery 55 was closed over wire 61, roller contacts and conducting sleeve 72, 73 and 74, Fig. 5, (sleeve 73 has now been thrown up between contacts 72 and 74, forming connection) over wire 61', roller contacts and conducting sleeve 75, 76 and 77, Fig. 6, (sleeve 75 is up between contacts 76 and 77) over wire 61'', through local 30 current relay coil 51, Fig. 7, and back to zinc pole of battery 55 over wire 61'''. This local current sustains the lever 49, Fig. 7, attracted in vertical position until the instruments are reset.

The small relay 191, Fig. 7, is installed 40 with the intention to interrupt in all the intermediary stations locked out, the connection from these stations' selecting apparatus with line 1, which is lead in through wire 218 and 222, Fig. 4, to insure that nobody 45 can take the line, or be able to make any disturbances when other stations are in communication. At the moment the auxiliary apparatus, Fig. 6, rocked over, a path was formed for the local current through relay 50 191, Fig. 7, (which breaks said connection) from battery 54, over wire 56, union 192, wire 193, roller contacts and connecting sleeve 194, 195 and 196, Fig. 5, wire 197, contact screw 198, Fig. 6, armature 35, 55 (which is thrown over in position O and therefore resting on said screw) union 68, Fig. 6, roller contacts and conducting sleeve 199, 200 and 201. (conducting sleeve 200 is then down between contacts 199 and 201) 60 wire 202, through coil 191, Fig. 7, and back to zinc pole of battery 54. This keeps lever 191' of relay 191 attracted, cutting the connection over wire 171'. This would be the position of that relay 191 in an intermediary station while the line is occupied, but in

the station set for communication the connection over lever 191' is not cut at all, for in that case the auxiliary apparatus, Fig. 5, has been caused to rock over too, and this cuts the wire 56, 192 and 193 from said battery 54, at roller contacts 194 and 196 as the next insulating sleeve has been thrown down between those contacts and that connecting link is then interrupted there, so 70 relay 191, Fig. 7, is not affected. This describes the setting for communication of the first station, and the next 48 stations have now to be locked out of connection. The next following current pulsation on its way to the second station on the northern section 80 flows through the operating station from battery 121, Fig. 1, (this is not followed this time by any pulsation from battery 122 until the pushed out contact 123 for station 50 reaches the contact brush 125) 85 out over wire 167, contact posts and sleeve 168, 169 and 170, wire 293, union 302, wire 171, Fig. 2, as already described, wire 171, Fig. 7, lever 49, contact post 172, wire 173, roller contact 174, Fig. 6, but as the insulating sleeve 204 has been thrown down between contact 174 and 176, the current flows up to roller contacts and conducting sleeve 205, 206, and 207. (conducting sleeve 206 is down between 205 and 207) over wire 208, 90 key 137, Fig. 18, telephone contact post 209, over wire 210, (it cannot take the other wire 274', Fig. 4, as this is cut at roller contacts and insulating sleeve 271, 272 and 273) 95 relay lever 38, Fig. 5, wire 211, roller contacts and conducting sleeve 212, 213 and 214, (conducting sleeve 214 is up between 212 and 213) over union 215, union 217, union 217', wire 218, Figs. 4, 5, 6, and 7, wire 218 Fig. 2, over roller contacts and 105 conducting sleeve 219, 220 and 221, over wire 222, Fig. 2, wire 222, Figs. 4, 5, 6, and 7, and out at 280 Fig. 4, on line 1 to said second station. The said second station is also represented graphically in the same 110 Figs. 4, 5, 6, 7, 1, 2, and 3, but it must be remembered the various apparatus are now to be considered in normal position. The pulsations enter the second station as coming from the south, L. 1 over roller contacts 115 and conducting sleeve 294, 295 and 296, Fig. 2, wire 278', contact plate 115, contact spring 114, (which is not pushed out in the intermediary stations and therefore forms contact with plates 115) union 301, wire 300, 120 union 299, wire 171, Fig. 2, wire 171, Fig. 7, lever 49, post 172, wire 173, roller contacts and connecting sleeve 174, 175 and 176, Fig. 6, through magnet coils first winding 177 and 178, union 180 and back over L. 2 to 125 zinc pole of battery 121. This operation shifted the armature 35 over to position O, wherewith the local current through the bridging relay coils 44 and 45, Fig. 7, is interrupted, and the levers 46, 47, 48 and 49, 130

fall back all of them, and as auxiliary apparatus, Fig. 5, is not set when only the locking out of stations takes place, none of the levers are lifted up again. Local circuit from battery 54, over wire 56, union 192, wire 193, forms connection this time over contacts and conducting sleeve 194, 195 and 196, Fig. 5, wire 197, screw 198, Fig. 6, armature 35, (this armature rests on screw 198) roller contacts and conducting sleeve 199, 200 and 201, wire 202, through coil 191, Fig. 7, and back to zinc pole, attracts lever 191 until the resetting of all the apparatus takes place. This second station on the northern section from the operating station is now locked out and the next current pulsation designed for the third station flows over the same described way, taking its course over last locked out station's lever 49, Fig. 7, contact post 60, (as lever 49 has fallen back on that post) and out over L. 1 to the next station, and this same operation is repeated 48 times, but all in such quick succession that it does not take half a second to have both communicating stations set and the 49 locked out. The 50th is now set just in the same way as described for station 10, but in this case the connecting wheels 20, 21 and 22, Fig. 1, stop as the plug 113 now comes across the stopping pin 128, contact brush 25, Fig. 1, slips into the cavity 130, Fig. 16, and breaks the local motor current, and the desired party is called up. If the connection had been made by a central office both the communicating parties would now be rung up at the same time, and the party nearest the central office could depress key 137, Fig. 18, so that the central office would hear nothing of the conversation.

40 Where central offices operate the connections the subscribers need no selecting apparatus, and only two auxiliary apparatus would be required, like those represented in Figs. 5 and 6, with bridging relays, Fig. 7, the same as is the case with the afore-mentioned installations on the extra third line in circular systems for interurban communication.

50 After finishing a conversation the plug 113 is taken out of the selecting apparatus, Fig. 1, and this puts the motor in movement, automatically, the connections for outgoing currents are cut off, all in the afore-described way. The motor is stopped an instant after 55 at its stationary place, as above described. Plug 113 is now inserted in the resetting apparatus, Fig. 3, it drops just back of the spring contact 223, and it establishes a local motor and a main line current circuit at the same time, from batteries 224 and 225, over contact screw 226, supporting rack arm 227, central piece of plug 228, supporting rack arm 229, contact screw 230, contact 231, spring contact 223, and here at union 233 the said currents part, the local current from 60 battery 224 flows through the motor and back to the zinc pole, starting the motor. The main line, or resetting, current makes its path over L. 1 and back through earth. It continues from union 233 over wire 234, 70 roller contacts and conducting sleeve 235, 236 and 237 of the line changing apparatus, Fig. 2, over union 302, wire 171, Fig. 2, wire 171, Fig. 7, bridging relay lever 49, down that lever, through core of relay 51, 75 Fig. 7, over spiral wire to lever 238, as this is attracted against post 239 in the stations set for communication, it flows over that post, wire 241, roller contacts and conducting sleeve 62, 63 and 64, Fig. 5, (conducting sleeve 64 is up between 62 and 63) down through second winding of magnet coils 186 and 187 and to earth. This operation throws the armature 34, Fig. 5, back into resting position R, and it interrupts the local current through small relay coil 51, Fig. 7, which causes the lever 238 to fall back on post 240, and the resetting current, (which is flowing out constantly without cessation till all the instruments have been reset) flows 80 now over contact post 240, wire 242, lever 48, post 59, wire 243¹, Fig. 7, roller contacts and conducting sleeve 69, 70 and 71, Fig. 6, through second winding of magnet coils 177 and 178 to earth. This operation rocks the 90 armature 35, Fig. 6, back again in its resting position and it reestablishes the local circuit through the bridging relay coils 44 and 45, Fig. 7, which attract the levers 46, 47, 48, and 49, lifting them into their upright position. 95

When the auxiliary apparatus, Fig. 5, is reset, a small fraction of the current may take its way for an instant over lever 49, post 172, wire 173, roller contacts and conducting sleeve 205, 206 and 207, Fig. 6, wire 208, key 137, Fig. 18, telephone contact 209, wire 210, lever 38, Fig. 5, wire 211, contacts and conducting sleeve 212, 213 and 214, union 215, union 217, and out on the line 105 to the next station, but this is scarcely an instant, and it is only to meet greater resistance over a longer path and through another bridging relay, and magnet coils to earth (if that following station be set or locked out) but this path is cut off at the first following station in normal position, so the greatest part of the current flows 110 through the coils 186 and 187, Fig. 5, to earth, attracting the armature 38, this interrupts the path for this insignificant stray current over wire 211 and it flows therefore undivided an instant after in all its force through the second winding of said coils to earth, throwing the armature 38 over into 115 position R. After resetting a station this resetting current, having L. 1 and earth for circuit conductors, does not take the path over lever 49, Fig. 7, post 172, wire 173, 120 roller contacts and conducting sleeve 174, 125 130

175, and 176, Fig. 6, through magnet coils 177 and 178 to L. 2, but the way designed for it, namely, at the moment the bridging relays have been attracted by coils 44 and 45, 5 Fig. 7, the current for resetting stations ahead finds its path from wire 171, Fig. 7, over lever 49, through armature or core of coil 51, Fig. 7, union 238, relay lever 53, post 240, wire 242, lever 48, over that and 10 over post 244, union 246 and out over L. 1 to the next station. As that station and the next following 48 are locked out stations and the bridging levers 46, 47, 48 and 49, Fig. 7, are resting on their back stops, the 15 current will come in over lever 49, Fig. 7, down that lever, over post 245, union 247, wire 242, lever 48, post 59, wire 243¹, roller contacts and conducting sleeve 69, 70 and 71, Fig. 6, through second winding of coils 177 20 and 178 to earth, shifting the armature 35 over to position R, reestablishing the local current and raising the bridging levers again. The small part of the resetting current escaping over lever 49, Fig. 7, post 60, 25 and out on L. 1, is instantaneously checked as the current passes the coils 177 and 178, Fig. 6, attracting the lever 40, which interrupts the L. 1, that is lead down to that relay with that object, and this makes the full 30 force of the current pass the designed way, through coils 177 and 178. This same operation is repeated until all stations are reset, station 50 is reset in the same way as above described for station 10.

35 The aforescribed way of establishing connection by the subscribers themselves, and doing the resetting quite imperceptibly and automatically, demonstrates the operation one way only, which is ahead, or over 40 the northern section from the operating station, but connections can also be made in the other direction, or over the southern section from the operating station. A subscriber on a circular or terminal line system 45 can perceive when the line is taken ahead of him by some other subscriber, for when he reaches the operating subscriber's selecting apparatus, the line is interrupted, he can notice it upon ringing up that the line is 50 cut somewhere, and with an extra little battery and a sounder, which could be constantly kept in use, or switched in, in order to test the line, and by counting the times the sounder sounds, any operator can know 55 exactly which station has taken the line, or where the line is interrupted, and if he does not want to wait till the line is free, he can make connections over the section back of him, and it is just for such purposes that 60 the extra line changing apparatus, Fig. 2, and the extra auxiliary apparatus, Fig. 4, have been installed. The selecting disk 22, Figs. 1 and 17, will to that end have the plug holes numerated above with the numbers to take when working ahead and below 65

with the numbers that must be used when working over the back or southern section. The normal position of this line changing apparatus, Fig. 2, must be described preliminarily. The through connection for an operating current over that, in reference to 70 an intermediary station before it is locked out, is for a current coming in from the southern section over roller contacts and conducting sleeve 294, 295, and 296, Fig. 2, wire 278¹, connecting plate 115, Fig. 1, (plug 75 113 in intermediary station is not inserted and plates 115 and contact springs 114 are in connection) over spring 114, union 301, wire 300, union 299, wire 171, Figs. 2 and 7, and here the current enters the auxiliary apparatus on its operating mission as already described.

The through connection for an operating current in reference to an intermediary station before locked out over the same instrument and, from the northern section, is over 85 L. 1, Fig. 4, over union 280 and wire 222, Figs. 4-7, wire 222, Figs. 1 and 2, roller contacts and conducting sleeve 219, 220, and 221, Fig. 2, wire 218, Figs. 4-7, entering the auxiliary apparatus over union 259 and lever 46, Fig. 7, on its way of operation. The through connection for an operating or telephone current from the southern section 90 after such an intermediary station has been locked out, is the same as just described for a station before it was locked out, while the description for the current pulsations from the northern section after a station has been 95 locked out is as follows: After a station is locked out and the relay 191, Fig. 7, is energized by a local current through that relay's coil, which has been already described, and the relay levers 304 and 191', Fig. 7, have 100 been attracted, a path opens for the current in over union 280, Fig. 4, wire 222, Figs. 4-7, union 308, Fig. 7, wire 306, lever 304 of relay 191, connecting post 303, wire 307, 105 wire 171'', union 258, wire 218, union 217, L. 1, union 246, Fig. 7, post 244, lever 48, wire 242, post 240 of relay 51, through core of same relay, lever 49, wire 171, Figs. 7 and 2, union 299, wire 300, union 301, Fig. 110 1, spring 114, connecting plate 115, wire 278¹, roller contacts and conducting sleeve 294, 295 and 296, and out over the southern section. The same current can partly take 115 its path over wire 222, Fig. 7, roller contacts and conducting sleeve 219, 220, and 221, and back over wire 218, joining the other part on the same course, this division in this case makes no difference in the operation.

120 Another function of the line changing apparatus, Fig. 2, and the small relay 191, Fig. 7, is to completely prevent intermediate stations from taking the line when it is occupied, disregarding the sign indicating 125 130

that the line is busy. When a subscriber therefore untimely inserts his plug 113 in his selecting apparatus, Fig. 1, the relay 191, Fig. 7, is at such an occasion energized (which is the case in all locked out stations but not in stations set for communication) and lever 191' is attracted, so when spring 114, Fig. 1, is pushed out, a local circuit is established from battery 225, Fig. 3, at union 309, over wire 310, union 312, wire 171', Figs. 1 and 7, lever 191' of relay 191, connecting post 313, wire 311, Fig. 1, connecting screw 314, spring 114, (this spring combines two conductors insulated from one another by a sheet of insulating material) contact bracket 315, wire 316, roller contacts and conducting sleeve 317, 318 and 319, Fig. 2, (switching attachment is in position R,) wire 320, union 321, wire 322, magnet coils 251 and 252 and back over wire 253 to zinc pole. This throws the armature 254, Fig. 2, over to position 0, wherewith this last described local circuit was interrupted at roller contacts 317 and 319, as the insulating sleeve 323 was thrown down between contacts 317 and 319. If telephone communication or connecting operations should be going on at such a moment when somebody is trying to take the line, the interruption caused is of a lightning's brevity, and it would scarcely be noticed in the telephone as a "tick." Another path is instantaneously substituted for the through current, instead of flowing through the selecting apparatus, Fig. 1, as above described, it flows, after such a shifting, over wire 171, Fig. 2, roller contacts and conducting sleeve 278, 279 and 220 and out on L. 1, or vice versa. The other paths over union 299 and wire 300, or over union 302 and wire 293, are at the same time interrupted, as will be seen following the wires and having in mind that the magnet has been rocked over to position 0. A current passing over wire 222 and 218, Figs. 4-7 and Fig. 2, is now interrupted at roller contacts 219 and 221, Fig. 2, as an insulating sleeve has been thrown down between them, and will flow over union 308, Fig. 7, wire 306, lever 304, post 303, wire 307, wire 171'', union 258, and over wire 218 to its destination.

If the subscriber who tries to take the line when it is occupied goes further and puts his machine in movement, the paths for the current pulsations from battery 121 are cut off, the one at roller contacts 168 and 170, Fig. 2, as insulating sleeve 255 has been thrown up between them. The other path over roller contacts and conducting sleeve 256, 257 and 324, Fig. 2, and over wire 171' is cut in relay 191, Fig. 7, as the relay lever 191' is attracted against post 313. As only the battery current from battery 121 on its way of operation over L. 1, opens paths for the current from battery 122,

through earth, no pulsation can flow out from that either, so it is absolutely impossible for any intermediary station to interrupt any communicating parties, or any operating subscriber who has been the first, only by one instant, to take the line, and no intermediary station can know what parties are in communication, and no casual talk can take place in this system by parties trying to break in on an established connection. When this line changing apparatus has been thrown over untimely by somebody, it will be reset as soon as the subscriber discovers his mistake and puts the plug back again in its resting place, the rack in the resetting apparatus. How the resetting is performed automatically has already been described. In establishing connection backward, or over the southern section from the operating station, this line changing apparatus gives the wire 171, Figs. 7 and 2, a direct connection over roller contacts and conducting sleeve 278, 279 and 220 out on L. 1, southern section, at the moment the armature 254 has been thrown over to position 0. The current from battery 121 over wire 167, Fig. 2, is also changed in this apparatus at roller contacts and connecting sleeve 168, 169 and 170, so that instead of flowing over those and up over wire 171, it flows over roller contacts and conducting sleeve 256, 257, and 324, over wire 171'. The operation is the following: Key 248, Fig. 2, is depressed an instant wherewith a current pulsation flows from battery 225, Fig. 3, over wire 249, key 248, wire 250, Fig. 2, through first winding of magnet coils 251 and 252, over wire 253 and back to zinc pole. This operation throws the armature 254 over to position 0, and when the plug 113 is inserted in the selecting apparatus, Fig. 1, and the motor is started, the current from battery 121, flows over brush contact 120, conducting rail 119, spring contact 117, union 166, wire 167 and, as the insulating sleeve 255, Fig. 2, has been thrown up between roller contacts 168 and 170 and the conducting sleeve 169 up between contacts 256 and 257, the current takes that last said path over wire 171', Figs. 2 and 7, lever 191' of relay 191, (this lever is not attracted and will not be as the first station to be set is always the operating station, and stations set for communication keep the local circuit over relay 191 cut, as already described) wire 171'', union 258, wire 218, Figs. 4-7, union 217', over L. 1 to union 259, Fig. 7, over that and wire 260, lever 46, post 261, wire 262, roller contacts and conducting sleeve 263, 264 and 265, Fig. 4, through first winding of magnet coils 266 and 267 and down to union 268 and back over line 2. This operation throws armature 33 over to position 0, and the local current maintaining the four levers of the 130

bridging relays, is interrupted, making those levers fall back, except lever 46. This current pulsation was followed by another from battery 122, through earth, ascending 5 over wire 268', stop 269, Fig. 4, relay lever 36, (which is at that moment attracted by the core of coils 266 and 267 by the passing current from battery 121) wire 270, roller contacts and conducting sleeve 183, 184 and 10 185, Fig. 5, through magnet coils 186 and 187, over union 189, and back over L. 2. This operation throws the armature 34, Fig. 5, over to position 0, and establishes a local current through small relay 50, Fig. 7, from 15 battery 55, over wire 61, roller contacts and conducting sleeve 72, 73 and 74, Fig. 5, (the conducting sleeve being now between 72 and 74) wire 61' to union 78, where it takes its path over wire 79, roller contacts and 20 conducting sleeve 80, 81 and 82, Fig. 4, wire 79', through coil of relay 50, Fig. 7, and back. This station is now set for communication and the next current pulsation from battery 121 is through this set station, and as 25 the following current pulsations are meant for locking out purposes, they flow in over same path as the above described from same battery to union 259, L. 1, Fig. 7, over wire 260, lever 46, (which is in upright position) 30 wire 262, roller contacts and conducting sleeve 271, 272 and 273, over wire 274', Fig. 4, telephone contact 209, Fig. 18, over wire 210, lever 38, Fig. 5, wire 211, roller contacts and conducting sleeve 212, 213 and 214, 35 (conducting sleeve 214 is now between 212 and 213) wire 274, union 275, Fig. 7, wire 276, union 277, contact post 60, (lever 49 is now resting on that post while lever 46 is maintained upright) lever 49, wire 171, Figs. 40 7 and 2, union 299, wire 300, Fig. 2, union 301, Fig. 1, spring 114, (which is in normal position and not pushed out) connecting plate 115, wire 278', roller contacts and conducting sleeve 294, 295 and 296 and out over 45 L. 1 to the next station, the second station on this backward operation. This last described current cannot take the path from wire 171, Fig. 2, over union 302 and wire 298, as this is interrupted at the spring contact 117, Fig. 1, and wire 171, Fig. 2, is interrupted at contact 278 and 279 in the switching attachment. 50 Continuing the back operation over the southern section, the second station is locked out by the current coming in over L. 1. Taking for this second station, to the rear, the apparatus at the station calling, comprised in Figs. 1-7, the current entering by line 1, union 280, flows over wire 222, roller contacts and conducting sleeve 219, 220 and 221, Fig. 2, wire 218, Figs. 4-7, union 217', Fig. 4, union 259, Fig. 7, wire 260, lever 46 of bridging relay 44, contact post 261, wire 262, roller contacts and conducting sleeve 263, 264 and 265, Fig. 4, through magnet 55 coils 266 and 267, union 268 and over L. 2 back. The passing of this current pulsation through the said magnet coils throws the magnet 33 over into position 0, wherewith all the levers 46, 47, 48 and 49 of bridging relays 44 and 45, Fig. 7, are released and fall back, as the local circuit current maintaining them in upright position is broken at the moment this magnet opened the gap between screw 65 and armature 33, Fig. 4. 60 A local current through relay 191, Fig. 7, is established in the same way as before described, at the moment the auxiliary apparatus, Fig. 6, operates the locking out of connections. This operation locked that second back station out and the next current pulsation will come in through this second back station over L. 1, union 259, Fig. 7, lever 46, contact post 57, union 275, wire 276, union 277, contact post 60, lever 49, 65 wire 171, Figs. 7 and 2, union 299, wire 300, union 301, Fig. 1, spring 114, (which is not pushed out) contact plates 115, wire 278', roller contact and conducting sleeve 294, 295 and 296, Fig. 2, and out over L. 1, south 70 and to the third back station. The following stations are all locked out in the same way, and the selected station is also set in the same way as above described. 75 The resetting of the stations back or over the southern section from the operating party is the same as already described for the northern section, but the resetting of the line changing apparatus, Fig. 2, does not take place until all the other stations 80 from the same operating stations apparatus to the selected party's are reset. A moment before the wheel 31, Fig. 3, finishes its rotation and the hook-like spring contact 223, grasps around the plug and stops the movement, the spring contact on wheel 31, (or bracket contact) touches the plug and a current pulsation flows from battery 225, over 85 supporting arm 226, Fig. 3, over the plug to bracket contact 336, (the resetting current L. 1 and earth, has already ceased to flow as the resetting is finished before the wheel comes so near the plug, and as soon as 90 all the stations are reset no current flows out notwithstanding that the resetting wheel may not have finished its rotation) 95 over wire 337, through second winding of magnet coils 251 and 252, Fig. 2, and back over wire 253 to zinc pole, wherewith this apparatus is reset. The arrangement of this 100 automatic line changing apparatus relieves the operating party from any trouble due to forgetting to switch back, if a switch were used instead. 105 If during the resetting of the stations 110 back over a southern section current comes in over line 1, from the northern section, union 259, Fig. 7, flowing through auxiliary apparatus, Fig. 4, a breach in L. 1 on the southern section, back of apparatus, Fig. 2, 115 120

is opened an instant while the current flows through the magnet coils 266 and 267, and while the lever 37, Fig. 4, is attracted. This is made with the same object as the aforementioned breach or interruption at the relay 40, Fig. 6, when a resetting current is coming in from the southern section, to compel the full force of the current to flow in through these auxiliary apparatus. The place where this breach, Fig. 2, is made is indicated by dotted lines, and it is understood that while the wires are not led to that point, it is in order to avoid describing detailed paths each time the passage of currents should have taken that way. The wires 338 and 339, Fig. 4, are the conductors to that breach, leading to the interrupting relay 37, Fig. 4. The interchanging installation is destined for interconnection from trunk lines to city or rural systems in connection with a central station, which may connect a number of city systems.

Selecting apparatus are used just as above for setting and locking out of stations and with the same object, but a central station needs no auxiliary apparatus or bridging relays, a telephone connected with L. 2, and which can be switched into connection with L. 1, when required, is all that is needed. The operation in the central office for the selection of the subscribers is the same as before described for the subscribers on circular or terminal lines, except that there are no first auxiliary apparatus to be set for communication, and that two plugs will generally be used, a smaller plug in the selecting disk's smaller holes, Fig. 17, below the series of larger holes. This is inserted in the hole bearing the subscriber's number who is nearest the central office, and the larger plug, 113, Fig. 1, is inserted in the hole corresponding to the subscriber who is farthest out on the line. The smaller plug will cause the first station to be set just in the same way as described, but as the stopping pin 128, Fig. 1, does not reach this plug, the apparatus moves on until the larger plug stops the movement, whereafter the stations of the parties who want to be connected are rung up, and communication is established. It must be understood that the small plug pushes the spring contact 123, Fig. 1, out in touch with the connecting or contact brush 125, just as the large plug does it, though not so far out but to the same effect, and therewith causing the current pulsations from battery 122 to flow out and set the stations in whose number holes the plugs have been inserted. A third line is generally used for interurban connections, not on the trunk lines, but in cities and rural districts, except in small places where there are only a limited number of subscribers on the system. Inter-

changing stations are locked out or set for interchanging just in the same way as above described for locking out or setting for communication, though the wiring of the instruments is somewhat different.

For the setting of a station in one city for a party who may have ordered connection with another subscriber in another city, three small plugs and a larger one are required and same are inserted in the disks in the central station. The first small plug sets the first interchanging installation (or interurban exchange switches), the second the subscriber's station in the first city; the third will set the second interchanging installation's switch, and the fourth, the large plug, will set the called party's apparatus in the farthest away station and stop the movement of the connecting wheels when coming across the stopping pin 128, and connections are then established and both connecting parties are rung up. Fig. 20 gives a sectional view of the positions of the plugs and the radial spring contact, which for interurban exchange purposes is a double spring 117 and 117', the large plug, which is put in for the last station to be set for communication, pushes both those springs out protuberantly, wherewith contact plate 127 on the radial spring 117' is pushed back from connection with connecting brush 25, leaving an empty space, 130, which said connecting brush slips into and thus interrupting the local motor current, at the same time as the stopping pin 128 stops the movement of the wheels. The small plugs do not push the second radial spring 117' out, as holes are made in those springs where those plugs are inserted, so large that the small plugs slip through and leaves it in its resting place, forming uninterrupted connection with the series of those plates and brush contact 25. The larger plug engages both said radial springs 117 and 117' with its shoulders and pushes them out both with its wider circumference.

Fig. 21 is a front view of the connecting disk, and shows in a more detailed way the position of the plugs as inserted for an interurban connection. Suppose that station or subscriber 4 on local city or rural system *a* wants connection with subscriber 36 on city system *C*, the first small plug is inserted in the small plug hole *A*, which sets the interurban exchange switch at city *A*; the next small plug is inserted in plug hole 4, which sets the corresponding subscriber's apparatus in position for communication; the third small plug is inserted in small plug hole *C*, which sets that interurban exchange switch at city *C*, and the fourth plug, the large one, making the stop, is inserted in the large plug hole 36, whereafter the wheels are put into rotary movement and when

they stop the two subscribers Nos. 4 and 36 are rung up at the same time. Spring 114 is not pushed out by the small plugs, as that is done only once in each series of operations by the large plug. Small plugs are used in the same way on local city systems in cases when any subscribers would speak to several other subscribers at the same time. At the central station there is no operating station or apparatus to be set, so the connecting wheels can be used for further operations on lines, as interurban lines, connecting a large number of subscribers and interurban exchange places, every time they are halted at their initial stopping places, making them revolve a second or several times, withholding the large plug to be inserted in the last subscriber's large plug hole, effecting the stop at that subscriber's number, after all the locking out and setting of stations according to the use of the small plugs, successively inserted in the holes, corresponding to the above indication for setting the selector, and according to the repeated series of numeration as shown on the connecting disk, Fig. 21.

When an interchanging installation is set for interconnecting purposes the current comes in over L. 1, lever 94, Fig. 10, connecting post 110, wire 341, roller contacts and conducting sleeve 342, 343 and 344, Fig. 9, through magnet coils 345 and 346 to L. 2 and back to zinc pole of battery 121, Fig. 1. The passing of this current through said magnet coils throws the armature 86 over to position O, and the rocking over of that interrupted at 108, Fig. 9, the local circuit from battery 97, Fig. 10, which forms its circuit over wire 102, union 105, wire 106, union 107, Fig. 9, armature 86, contact screw 108, over wire 106', through coil 92, Fig. 10, wire 106'' and back to zinc pole. Lever 94 of bridging relay 92 would now fall back if it were not for another current flowing through earth from battery 122, Fig. 1 and up through wire 347, Fig. 9, over lever 90, (this is attracted against post 348 while the other current from battery 121 passes the coils 345 and 346) over wire 349, roller contacts and conducting sleeve 350 and 351 and 352, Fig. 8, through magnet coils 353 and 354 to L. 2 and back to zinc pole of battery 122, which throws the armature 85 over into position O and establishes a local current that sustains the lever 94 in upright position, in the way as described in the following: The armature 85, Fig. 8, is therewith thrown over to position O. This interrupts at 103, Fig. 8, the local current which makes its circuit from battery 97, Fig. 10, over wire 102, union 104, Fig. 8, armature 85, connecting screw 103, wire 102', coil 91, Fig. 10, wire 102'' to the zinc pole, and the lever 93, Fig. 10, falls back where

it remains till the apparatus are reset. A local current is established from battery 96, Fig. 10, wire 98, roller contacts and conducting sleeve 99, 100 and 101, Fig. 8, (sleeve 100 is thrown up between 99 and 101) wire 98', through coils of local current relay 95, Fig. 10, over wire 98'' and back to zinc pole. Last said relay sustains lever 94, Fig. 10, in upright position. This installation is now set for interchanging purposes and the next current pulsation goes to operate the locking out or the setting of the next station in the city system, Fig. 11. The current comes in as before, over lever 94, and post 110, Fig. 10, wire 341, as the insulating sleeve 358, Fig. 9, has been thrown down between roller contacts 342 and 344, the current flows over roller contacts and conducting sleeve 355, 356 and 357, over wire 358', lever 89, wire 359, over L. 3, locking out the stations and setting the one selected, locking out the other stations on that same system to the opening of the circular system, ascending over wire 360, over roller contacts and conducting sleeve 361, 362 and 363, Fig. 9, (conducting sleeve 363 is now up between contacts 361 and 363) wire 364, lever 87, wire 373, lever 93 of bridging relay 91, Fig. 10, over post 377, (lever 93 is in resting position) wire 374, union 375 and out on L. 1 to operate the locking out of other stations on the trunk line and city systems. Where no setting for communication in this system, Fig. 11, has to be done, the interchanging installation is locked out just as another station, only armature 86, Fig. 9, is rocked over, the lever 94, Fig. 10, falls back on post 376 and the circuit current takes its path over that and out over L. 1. The resetting is done just in the same way as the other set or locked out stations, and is done in the same course of operation together with those.

L. 2 is always reserved for all the subscribers for the purpose of delivering the central office orders for connecting them with interurban parties. If a party is not in communication over L. 1, that is to say, if his auxiliary apparatus, Fig. 5, is not set for communication, he can call the central station up any time, over wire 210, lever 38, Fig. 5, wire 211, roller contacts and conducting sleeve 365, 366 and 367, (this path is closed when a station is set for communication over L. 1) wire 378, key 112, wire 380, union 379 and over L. 2. The magneto bell current cannot flow out any other way, if the operating party's station is in normal position, because the line 274' from telephone contact 209, Fig. 18, is interrupted at roller contacts 271 and 272, Fig. 4, and the wire 208 from same contact, is interrupted at roller contacts 204 and 205, Fig. 6, or if any of these auxiliary apparatus are locked out,

the same wires from telephone contact 209 are interrupted at connecting posts 261 and 172 of bridging relays 44 and 45, Fig. 7. Adding another small battery to the connecting brush 120, Fig. 1, with earth as return conductor, (which is not indicated as it makes no change in the connections in the selecting apparatus to add such a battery) and two small extra interrupting coils, or 5 relays 400 and 401, as shown in Fig. 7^a, the locking out and setting of stations may be effected in a little different way, if that should prove more satisfactory. The resetting of the stations can also be done differently, for which purpose another relay 402, 10 Fig. 7^a can be installed. The locking out and the setting of stations is in that case made with two batteries, the customary battery used as per above, making its circuit 15 through L. 1 and L. 2 back, while the small added battery makes its circuit through L. 1 and earth back. The wiring for this new 20 change in the apparatus is just the same as described and shown in Figs. 6 and 7, and the added wires are shown in Figs. 6^a and 7^a 25 with heavy lines. Both those battery currents enter the stations together at lever 49, Fig. 7^a, over contact post 172, the small battery current flows through coil 401, wire 403, union 404, to earth and back, while the other current from battery 121 flows the above-described way, over wire 173, contact 30 rollers and conducting sleeve 174, 175 and 35 176, Fig. 6^a, through magnet coils 177 and 178 to L. 2 and back. The small battery current, while passing through coil 401, Fig. 40 7^a, attracts both the interrupting lever 405 and the bridging lever 49, so that the last does not fall back until the current pulsation 45 has ceased to flow, and the lever 405, while being attracted, interrupts the path at post 406 for any fraction of current from battery 121 on its mission of locking out or setting, that might take its way over union 406, Fig. 7^a, wire 242, lever 48, post 244, lever 50 405, union 246, and out over L. 1 north, so this aggregation insures against any passing 55 of current further over the line till it has successively completed the locking out or setting of stations.

When the currents come in from L. 1 north, passing over lever 46, Fig. 7^a, the same operation takes place as just described, being then the other apparatus, Fig. 4, which 60 is operated upon, but this apparatus is not represented on the plan of the aggregated apparatus and lines as the course of the aggregated arrangement is easily understood, or is the same as the aforescribed for Fig. 65 4, with the addition of the same changes as described in Figs. 6^a and 7^a. The resetting is done, if this change in installation is adopted, with battery circuit out through earth and back over L. 2, ascending over

wire 407, union 404, wire 408, contact rollers 65 and connecting sleeve 409, 410' and 411 (connecting sleeve is in case of resetting thrown up between 409 and 410') wire 412, through coil 402 to L. 2 and back. This operation 70 attracts lever 413 wherewith local battery 70 410 closes a local circuit through that lever, over posts 415 and 416, wire 417, lever 53, (from here the current would first flow over post 239, Figs. 7 and 7^a, and over wire 241 75 to auxiliary apparatus, Fig. 5, and reset that, if the one in reference be a set station, for in that case the lever 53, Fig. 7^a would be attracted toward post 239) while supposing it be a locked out station, the current flows over post 240, Fig. 7^a, wire 242, 80 lever 48, post 59, roller contacts and conducting sleeve 69, 70 and 71, Figs. 7 and 7^a, through magnet coils 177 and 178 and back to battery 410, over wire 419. If it be the auxiliary apparatus, Fig. 4, that is to be 85 reset the same operation takes place, the same battery current (battery 410) would flow over post 416, but as auxiliary apparatus, Fig. 6, or 6^a, is in that case not thrown over, there is no path open for this local 90 current over the same wire as just described, the path is cut at roller contacts and conducting sleeve 69, 70 and 71, Fig. 6^a, so the current flows over union 418, wire 419', and over a corresponding path to auxiliary apparatus, Fig. 4, as that corresponding to the 95 section just described.

It will be seen that the connection between the cores of relays 50 and 51, Fig. 7, with their levers 52 and 53 is cut off in the 100 changed wiring, Fig. 7^a. That prevents the possibility of any fraction of current from the telephone battery escaping momentarily through earth, in case the magnet coils were not wound with high resistance enough. 105 This new change with described aggregated coils and wires insures completely against any fractional and momentary current escaping anywhere.

It is evident that this multi-party system 110 can be used and adapted by any telephone company for the purpose of economy in construction and reduction in rates for new aggregated subscribers, specially for a certain class having more limited use for the 115 telephone connection, and various apparatus may be constructed or connected with this same plan to obtain the same object, and I therefore do not wish to limit myself to the specific structure illustrated and described. 120

Having thus fully described my said invention, what I claim as new and desire to secure by Letters Patent is:

1. In a telephone system, the combination 125 of a pulsating selector, an automatic switch at the same station and controlled thereby, a source of current through the selector to said switch to set it for communication, like

switches at intermediary stations set by said source of current to lock out communication, means in each station apparatus for completing the setting thereof for communication, and a second source of current controlled by the selector to act solely upon said means at the two stations between which communication is to be established.

2. In a telephone system, the combination at each station of a pulsating selector, switches for partially setting the station for communication and for locking the station out of communication, and means for completing said setting for communication, a source of current operating through the selector of a calling station, for partially setting for communication that station and the station called, and for successively setting the switches of the intermediary stations in lock-out position, and a second source of current for completing the setting of the calling and called stations for communication.

3. In a telephone system, the combination at each station of a pulsating selector, switches for partially setting the station for communication to one side of the station, also switches for setting the station for communication to the other side thereof, means for locking the station out of communication with stations to either side thereof, means for completing said setting for communication, a source of current operating through the selector of the station calling for partially setting for communication that station and the station called, and for successively setting the switches of the stations between them in lock-out position, and a current over another path through the selector of the calling station for completing the setting of the calling and the called station for communication.

4. In a telephone system, the combination at each station of a pulsating selector, switches for setting the station for communication and for locking the station out of communication, a source of current operating through the selector of a calling station for partially setting it and the station called for in communication, and for cutting out of communication the intermediary stations, a source of current flowing also through the selector for completing the setting of the called station after the intermediary stations have been cut out, and a resetting device at each station whereby all affected stations may be returned to normal position after communication between the two connected stations has ceased.

5. In a telephone system, the combination at each station of a pulsating selector, switches assisting in setting the station for communication and in locking it out of com-

munication, relays coöperating with said switches in the setting and the cutting out 65 operation and current supply controlled by the selector for the actuation of said switches and relays.

6. In a telephone system, the combination at each station of a pulsating selector, 70 switches assisting in the setting of the station for communication ahead or to the rear, a line changing switch, relays assisting in the setting and cutting out operations, a resetting apparatus, and current supply for 75 the switches and relays controlled by the selector and the resetting apparatus.

7. In a telephone system, the combination with automatic switches at the stations, of a selector provided with rotary disks, circuit 80 connections to one of said disks whereby current pulsations are sent to the station, switches for partially setting two of the stations for communication and for cutting out the station between said two, and circuit 85 connections to another of the disks of the selector whereby current is sent to the switches of said two stations to complete the setting thereof for communication.

8. In a telephone system, the combination 90 with automatic switches at the stations, of an electrically driven rotary selector provided with a series of disk circuit makers and breakers, a source of current for driving the motor and controlled by one of said 95 disks, a source of current connected to another of said disks for acting upon the switches of called and intermediate stations, and a source of current connected to a third one of said disks for acting upon only the 100 stations seeking communication.

9. In a telephone system, the combination with automatic switches at the stations, of a rotary selector provided with a series of disks, one of which controls the motor 105 current of the selector and the others the operation of the said switches, a plug for insertion in said disks to determine the station called, and a stop for engagement with said plug when the switches of the called 110 station have been operated.

10. In a telephone system, the combination with automatic switches at the stations, of a rotary selector provided with a series of disks, one of which controls the motor current 115 of the selector and the others the operation of the said switches, a plug for insertion at different points in said disks to determine the station called, a stop for engaging said plug to limit the forward movement of 120 the selector, and a stop for halting the selector at the normal or initial position when the apparatus of the system are reset.

11. In a telephone system, the combination with a source of current, of a selector for 125 controlling the flow therefrom, and a series

of automatically rocking switches and relays at each station of the system whereby the path of the current through a station may be determined in accordance with the 5 setting of the selector.

12. In an automatic telephone system, a rocking switch consisting of electromagnets, an armature pivoted to be rocked thereby, an arch mounted on said armature and provided with insulated conducting sections,

and circuit terminals bearing at opposite points upon said arch.

In witness whereof, I have hereunto set my hand and seal at New York, N. Y., this 20th day of January, A. D. nineteen hundred and thirteen.

OTTO ASMUSSEN. [L. S.]

Witnesses:

AUGUSTO DE LASADA,

A. E. PARKER.
